LAUNDRY BAG

Donigan D. Towers, Rome, Ga., assignor to
Anchor Duck Mills, Rome, Ga., a corporation
of Georgia

Application August 25, 1932, Serial No. 630,339

10 Claims. (Cl. 150—1)

The present invention relates to bags or containers of the open mesh or net-woven type and has for one of its objects the provision of an improved laundry bag in which portions of the structure are arranged in such a novel manner as to secure greatly increased strength and long wearing qualities, particularly at joints or connections, without increasing the amount of material used.

10 The mesh or structure or bags of this type, in which, between repeated immersions and drying, articles or clothing are retained while being washed, is subject to very considerable stresses, torsional and otherwise. In order to meet these stresses various structural features, including fabrics having staggered or oblique weft or warp member, or right angularly disposed cooperating members, with numerous reinforcements have heretofore been proposed.

15 I have found that such reinforcements may tend to obstruct free movement of the washing fluid through the fabric and that the members or threads of the mesh, when relatively inclined, may tend to close or become aligned in adjoining parallel relation, at least during the torsional stresses, and another of the objects of this invention, generally stated, is to overcome such disadvantages.

20 Connected with the foregoing, a feature of the present construction, in which the weft and warp members are disposed right angularly, with relatively large openings, is a seam or elongate joint for the cooperating opposed body panels or sections of the bag.

25 This elongate joint, as shall hereinafter appear in detail, cooperating as it does with the weft threads or members of the fabric, which threads are straight and not bent or partly turned by the warp members, tends to form a cylindrical structure, which opposes the aforesaid torsional movement, thereby holding the openings of the mesh in wide condition for economical and efficient action of the washing fluid, to secure a further object of the invention.

30 The body panels, being continuous over the bottom of the bag, are of single piece structure. The seams, as already indicated, join these panels; and another feature of the invention, eliminating structure which has heretofore held moisture unduly and caused extra weight, is a rounded or curved portion which is disposed between and merges into said bottom and the ends of the elongate joints or seams.

35 The unitary panels are cut as a single piece from a web of material so that, when folded upon

itself, its opposite ends form the mouth or open end of the bag, at which another feature is disclosed.

This mouth, with a single run through the finishing machine, is formed with an endless overlapping or stitching in which the ends of warp members, one or more or the wefts, and the top ends of the seams or elongate joints are rolled and bound.

With the above indicated objects in view, and others which will hereinafter appear, the essential features of the present improved construction are herein clearly described, and fully illustrated in the accompanying drawings, in which:

Fig. 1 is an elevational view of the complete bag.

Fig. 2 is a plan view of woven material, as cut from a web, from which the bag is erected.

Fig. 3 is a horizontal section taken on the line 3—3 of Fig. 1, looking in the direction of the arrows.

Fig. 4 is a fragmentary detail of a curved lap seam, as taken from the bag in the cylindrical form.

Fig. 5 is an enlarged fragmentary view of the network fabric bag, as taken from the latter in the erect or cylindrical form, and showing the overedged top end.

Fig. 6 is an enlarged fragmentary view in which details of the warp and fill interengagement are shown; and

Fig. 7 is a somewhat diagrammatic view showing the manner of turning the blank of material into position to secure the sectionally curved seam of the cylindrical bag.

Similar characters of reference are applied to corresponding parts throughout the various views.

A blank of fabric cut from a web, as shown in Fig. 2, from which the bag is formed, consists in the present instance of a pair of panels or sections 7, 8, between which is a fold line A at the bottom B. As shown more clearly in Figs. 5 and 6 the meshes of this blank are relatively large and are formed by single straight cross weft members 3 of duck yarn, with which are incorporated warp threads, generally designated 4. The wefts 3 are continuous with each other, or formed from a single member, there being bent portions or loops 3' at the opposite edges of 50 the web.

The threads 4 are arranged in groups of three, two of which 12, 13, in continuous intersecting semicircular form, provide loops and engage the wefts 3 on one side of the latter; and then the

third thread 14 passes over the intersections of the first two, and between and below the said wefts, to form an interlocked structure. This construction is uniform throughout the main portion of the panels, but at their lateral boundary edges the members of the warp groups 4 are woven closely together to form selvedges, as seen for instance in Fig. 5, at the line 15.

On lateral margin, of the panel 7 is formed 10 with a selvedge 6, opposite which on the panel 8 is a selvedge 6'. The opposite margin of said panel 7 is formed with a selvedge 5, and opposite this latter selvedge and on the panel 8 is a co-operating selvedge 5'.

15 To set up or erect the bag, with the opposite panels foldable on the line A, the selvedges 6' and 5 are turned inwardly (see Figs. 7 and 3), so that the inner faces of the selvedges 6 and 6', and also those of 5 and 5' engage as shown in Fig. 3. 20 When the parts are turned as just stated, and the panel 7 is superposed upon the panel 8, the fold at 16 is superposed upon the outer edge of the selvedge 5', and the free edge of the selvedge 5 is superposed on the inner edge of the selvedge 5' 25 as indicated by the broken line of Fig. 3, and as shown in Fig. 7. In like manner the outer edge of the selvedge 6 becomes superposed upon the fold at 17 and the inner edge of the selvedge, as indicated by the broken line, becomes superposed upon the free edge of the selvedge 6', as indicated in Fig. 3.

Interposed portions of the strip or panels, between the respective selvedges, and at the line A, as clearly shown in Fig. 7, are in this manner 35 partly twisted or spirally turned, so that angular corners are eliminated and a curved and symmetrical junction, forming a strong corner lap, without bulk, is effected, as seen in Fig. 1. One longitudinal line of stitches for holding the selvedges together is shown at 7'. Any number of 40 these lines may be used, but about two are sufficient.

As thus turned the selvedges are disposed on opposite front and rear faces of the bag and on 45 different sides of the vertical central plane of the fold line A. When the articles to be washed are placed in the bag the latter takes a cylindrical form and the joined selvedges, which are then curved or about aligned with adjacent portions 50 7, 8, Fig. 4, form extremely strong and plain lap seams. The stresses are then taken transversely and their forces act in the direction indicated by the arrows C, D.

It is thus practically impossible for the wefts 55 to come into mutual contact, and the warp 4 and particularly the selvedges or lap seams contribute to bring about this result, in which the meshes of the panels, as already indicated, are held open during the washing operation.

60 The cut edges 9 and 10 of the network strip, which form the mouth or opening of the device are lashed or stitched with thread, as at 1, to prevent unravelling. This stitching is effected by a single run through a machine, during which 65 one or more of the wefts 3, the top ends of the lateral lap seams, and the ends of the warps 4, are slightly turned or rolled downwardly and outwardly to form a strong or heavy ring or band.

These top or edging stitches are mutually 70 joined or interlocked on the inner face of the mouth 11, so that the aforesaid band is of unitary construction, or endless.

As the heretofore described construction admits of considerable modification without departing 75 from the invention, the particular arrangements

shown should be taken as illustrative, and not in a limited sense; therefore, the scope of the protection contemplated is to be taken solely from the appended claims, interpreted as broadly as is consistent with the prior art.

Having thus described my invention, what I claim is:

1. In a laundry bag comprising a body having opposed unitary network panels, said panels having a fold line therebetween, inwardly turned 10 selvedges on opposed lateral sides of said panels, practically straight selvedges also on opposed lateral sides of said panels, said first selvedges engaging the second mentioned selvedges to form lap seams, and spiral portions continuous with 15 said respective selvedges at said line to close the seams thereof.

2. In a laundry bag comprising a body having opposed unitary network panels, said panels having a fold line therebetween, an inwardly 20 turned selvedge bounding one of said panels at one side of the latter, a practically straight selvedge bounding the opposite side of said panel, a practically straight selvedge bounding one side 25 of the other panel and engaging said inwardly turned panel to form a lap seam, an inwardly turned selvedge bounding the opposite side of the second mentioned panel and engaging the first mentioned straight selvedge to form another lap seam, and spiral selvedge portions disposed between the respective straight and inwardly turned selvedges and joining the latter at said line for sealing said seams thereof.

3. A laundry bag comprising a network strip 35 which is folded on its transverse central line to form a bottom, a panel, a coacting panel; said strip having lateral selvedges of close weave extending along both sides thereof, said first panel having the selvedge on one of its sides turned inwardly to engage the opposite selvedge on the 40 second panel for forming a lapped seam, and said first panel having the selvedge on the other side thereof engaged against the selvedge on the opposite side of the second mentioned panel, the last 45 mentioned selvedge being turned inwardly to form another lapped seam, the interposed portions of the selvedges between said seams being spirally turned to close the corners of the bag thereat.

4. A laundry bag comprising a network strip 50 which is folded on its transverse central line to form a bottom, a panel, a coacting panel, said strip having lateral selvedges of close weave extending along both sides thereof, said first panel having the selvedge on one of its sides turned inwardly to engage the opposite selvedge on the 55 second panel whereby to form a lapped seam, and said first panel having the selvedge on the other side thereof engaged against the selvedge on the opposite side of the second mentioned panel, the last 60 mentioned selvedge being turned inwardly to form another lapped seam, the interposed portions of the selvedges between said seams being spirally turned to form rounded bottom corners on the bag.

5. A laundry bag comprising in combination a network strip which is folded on its transverse central line to form a bottom, a panel, a coacting panel; said strip having lateral selvedges of close weave extending along both sides thereof, 70 said first panel having the selvedge on one of its sides turned inwardly to engage the opposite selvedge on the second panel, and said first panel having the selvedge on the other side thereof engaged against the selvedge on the opposite side 75

of the second mentioned panel, the last mentioned selvedge being also turned inwardly, the interposed portions of the selvedges at said line being spirally turned, and stitches holding said respective engaged selvedges together and forming lapped seams.

6. A laundry bag comprising in combination a network strip which is folded on its transverse central line to form a bottom, a panel, a coacting panel; said strip having lateral selvedges of close weave extending along both sides thereof, said first panel having the selvedge on one of its sides turned inwardly to engage the opposite selvedge on the second panel, and said first panel having the selvedge on the other side thereof engaged against the selvedge on the opposite side of the second mentioned panel, the last mentioned selvedge being also turned inwardly, the interposed portions of the selvedges at said line being spirally turned to close the corners of the bag thereat, said corners being rounded, and stitches holding said respective engaged selvedges together and forming lapped seams.

7. A bag comprising a strip of textile fabric which is folded on its transverse central line to provide opposed coacting panels; said strip having substantially straight marginal edges; one of said panels having the major portion of the outer face of one lateral margin thereof engaged against the major portion of the inner face of the corresponding margin of the opposite panel, there being a relatively small spirally disposed portion connecting the first portions at said line; said first panel having the major portion of the inner face of the other lateral margin thereof engaged against the major portion of the outer face of the corresponding margin of the second panel, there being also a relatively small spirally disposed portion of the second mentioned cooperating margins connecting the associated major portions at said line.

8. A bag comprising a strip of textile fabric which is folded on its transverse central line to

provide opposed coacting panels, said strip having lateral selvedges; one of said panels having the major portion of the outer face of one selvedge thereof engaged against the major portion of the inner face of the corresponding selvedge of the opposite panel, there being a relatively short spirally disposed portion connecting the first portions at one end of said line; said first panel having the major portion of the inner face of the other selvedge thereof engaged against the major portion of the outer face of the corresponding selvedge of the second panel, there being also a relatively short spirally disposed portion of the second mentioned cooperating selvedges connecting the associated major portions at the opposite end of said line.

9. A bag comprising a strip of textile fabric which is folded on its transverse central line to provide opposed panels, said panels having their adjoining lateral margins disposed in overlapping relation to provide two-ply seams, the inner face of one of the respective margins being engaged against the outer face of the mating margin, there being relatively small spirally turned portions between the respective margins at the opposite ends of said line, and stitches holding the coacting margins in position.

10. The herein described bag comprising a strip of textile fabric having opposed marginal selvedges, said strip being folded upon its transverse central line to provide coacting panels, said panels having their adjoining selvedge portions disposed in overlapping relation practically throughout their length to provide two-ply seams, the inner face of one of said respective portions being engaged against the outer face of the mating portion, stitches holding said respective portions engaged, and there being relatively small spiralled portions between the respective first portion whereby to contract the corners of the bag at the opposite ends of said line.

DONIGAN D. TOWERS.
